[57] CLAIM

The ornamental design for a glass cutter, substantially as shown and described.

DESCRIPTION

FIG. 1 is a top plan view of a glass cutter showing our new design;

FIG. 2 is a right side elevation view of the glass cutter of FIG. 1, the left side elevation view being a mirror image thereof;

FIG. 3 is a bottom plan view of the glass cutter shown in FIGS. 1 and 2;

FIG. 4 is a front elevation view of the glass cutter shown in FIGS. 1 to 3;

FIG. 5 is a cross-sectional view of the glass cutter, taken along the cutting plane 5—5 of FIG. 2;

FIG. 6 is a rear elevation view of the said glass cutter;

FIG. 7 is a top plan view of a modified embodiment of

the glass cutter shown in FIG. 1;

FIG. 8 is a right side elevation view of the glass cutter shown in FIG. 7, the left side elevation view being a mirror image thereof;

FIG. 9 is a bottom plan view of the glass cutter shown in FIGS. 7 and 8;

FIG. 10 is a front elevation view of the glass cutter shown in FIGS. 7 to 9;

FIG. 11 is a cross-sectional view of the glass cutter shown in FIGS. 7 to 10, taken along the cutting plane 11—11 of FIG. 8; and

FIG. 12 is a rear elevation view of the glass cutter shown in FIGS. 7 to 11.
